CLAIM

The ornamental design for a carrying bag as shown and described.

DESCRIPTION

FIG. 1 is a perspective view of carrying bag in accordance with the present application.

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the Figures show portions of the carrying bag that form no part of the claimed design. The broken lines immediately adjacent the shaded areas represent the bounds of the claimed design.

The shade lines in the Figures show contour and do not claim surface ornamentation or treatment.
